AIR COOLING SYSTEM FOR MOTORS

Jean Georges Dintilhac, Paris, France, assignor
to Society "Yacco S. A. F.", Paris, FranceApplication January 5, 1933, Serial No. 650,357
In Belgium January 27, 1932

22 Claims. (Cl. 123—171)

The present invention relates to air-cooling systems for motors and, more particularly, for motors of the star type such as are in common use in aviation.

5 One of the objects of the invention is to provide a cooling system operative to cool the different parts of the cylinder walls in such a manner that the temperature of these walls may be everywhere approximately maintained at the

10 same value.

A further object is to provide a cooling system preventing excessive cooling of the front parts of the cylinders where they come in contact with the air.

15 Still further objects will appear in the course of the detailed description now to be given with reference to the accompanying drawings, in which:

Figure 1 is a section taken on line 1—1 of Figure 2 (to be described) and showing one illustrative embodiment of the invention applied to an aviation motor;

Figure 2 is a front elevation of the cooling system represented in Figure 1;

25 Figure 3 represents, in a section taken on line 3—3 of Figure 4 (to be described), a second possible form of the invention;

Figure 4 is a front elevation of the assembly shown in Figure 3 with certain parts removed;

30 Figure 5 is a partial section taken on line 5—5 of Figure 6 and showing a third form of the invention;

Figure 6 is a front elevation of the cooling system illustrated in Figure 5 with certain parts removed;

Figure 7 is a section taken on line 7—7 of Figure 6 and showing a detail;

Figure 8 is a diagrammatic transverse section through a cylinder fitted with still another form

40 of cooling assembly;

Figure 9 illustrates, in the same manner as Figure 8, a modification of the latter;

Figure 10 is a front elevation of the form of cooling system shown in Figure 9;

45 Figures 11 and 12 illustrate in the same manner as Figures 9 and 10 still another modification of the cooling system represented in Figure 8;

Figure 13 represents, in transverse section, a 50 third modification of the cooling system illustrated in Figure 8.

Figure 14 is a plan view, partially in section, of a star type of aviation motor fitted with a cooling system similar to that shown in Figure

Figure 15 is a front elevation of the structure shown in Figure 14 with certain parts removed.

Referring to Figures 1 and 2 of the drawings there is shown an assembly composed of the following elements:

A cylindrical hood *a* enclosing a plurality of radially positioned cylinders *b*; a fixed front wall *c* having a plurality of diverging slots *c*⁰ formed therein, the walls of the slots being radial; a screen *d* mounted to slide in appropriate flanges formed on elements *a* or *c* and having a plurality of slots formed therein corresponding in shape to openings *c*⁰; a deflector or guard *g* bent to conform to the shape of cylinders *b* and covering the lower part thereof; an annular heating tube *e* communicating with the exhaust ports of the various cylinders and positioned in front, and adjacent to the central portion, of element *c*; and a Bowden wire *e*¹ operative to displace screen *d* and having its control extremity positioned adjacent the pilot.

Assuming that orifices *c*⁰ are positioned in line with cylinders *b*, inspection of the drawings will show that air impinging on the front portion of the cylinder is deflected away from the lower parts of the cylinders by screens *g*, thus ensuring a more effective cooling of the cylinder heads. At the same time, since slots *c*⁰ and *d*⁰ are divergent, a greater volume of air strikes the cylinder heads than those portions situated below the latter. Finally, the exhaust gases circulating in annular chamber *e* serve to pre-heat the air flowing toward the motor adjacent guards or screens *g*. In order to further increase the differential cooling between the cylinder heads and the rest of the cylinders, the propeller may be provided with a divergent head *f* tending to direct the air radially outward.

From the foregoing, it will be seen that each cylinder, being cooled more effectively at one end than the other, tends to have a more nearly equal temperature throughout the length thereof.

In the cooling system represented in Figures 3 and 4, means are provided for ensuring the cooling of both the back and front portions of each cylinder in such a manner that the temperature of these back and front portions may also be maintained at approximately the same value, contrarily to what occurs in the motors of the ordinary type, in which the front portions are too much cooled. In this modification, openings *c*⁰, instead of lying in line with the axes of the cylinders, as in Figures 1 and 2, are positioned to lie between adjacent cylinders and the air flowing toward the motor is deflected around towards the

back portions of the cylinders by a series of bent sheet metal screens or deflectors h provided with posterior radial exhaust ports, slots or openings h^0 . Inasmuch as openings h^0 increase in section 5 radially, the cylinder heads will be cooled more than subjacent portions of the cylinders.

The variant represented in Figures 5 and 6 differs from the ones shown in Figs. 3 and 4 only in that posterior radial slots h^0 are eliminated 10 and replaced by a plurality of triangular slots i^0 positioned behind the cylinders and formed in a plate i co-acting with deflectors h to direct the air toward the backs of the cylinders. Here, 15 annular exhaust e is placed behind, instead of in front, of the motor, but it is to be understood that it could, equally well, be mounted as shown in Figures 1 to 4. Preferably, openings i^0 are positioned peripherally so as to exert a differential cooling effect on the cylinder heads. Figs. 20 5 and 6 also illustrate a modified form of front screen capable of replacing those shown in Figures 1 to 4 wherein a first series of radial slots c^0 in the casing are positioned in the manner shown in Figures 3 and 4 (in line with the spaces 25 between adjacent cylinders) and are supplemented by a series of slots c^{10} positioned in line with some portion of each cylinder. As shown in Fig. 30 7 the opening c^{10} may be opened or closed by shifting the screen d with respect to the front wall c . The air projected backward by the propeller is directed into the motor hood obliquely in the direction of the spaces between adjacent cylinders through the slots c^{10} by means of deflectors 35 such as those indicated by the reference characters k and m in the screen and front wall respectively. This form of cooling assembly is fitted with a pair of opposed Bowden cables e^1 permitting rotation of screen d in either direction. Screen d is, of course, fitted with slots d^0 coacting 40 with openings c^0 and c^{10} .

The deflectors represented in Figures 3 to 7 need not take the particular form shown but may be replaced by equivalent structures.

Figures 8 to 13 show a cooling system adapted 45 for use on motor assemblies of any type whatever such as, for example, those employed on motor cycles.

In the cooling system shown in Figure 8, a sheet-metal guard g is placed in front of the cylinder and is flanked by a pair of postero-lateral sheet-metal deflectors q , positioned so that air may enter laterally at C and D, flow posteriorly between cylinder b and deflectors q and discharge posteriorly through an opening E. While 50 this assembly acts to effectively cool the sides and the back of the cylinder, its tendency is to 55 diminish the cooling effect exerted on the front portions of the latter.

If it be desired to increase the cooling effect 60 on the front portion of the cylinder, a vertical slot (Figs. 9 and 10) g^0 is provided laterally with respect to the axis of cylinder b and a deflector r acts to direct the incoming air toward the sides of the cylinder. The air currents follow substantially the direction of the arrows in Figure 65 9 and the front portions of the cylinder are cooled substantially to the same extent as the side and rear portions. In order to further assure a flow of air behind deflector d around the front of the cylinder, a supplemental deflector q^2 may be positioned inside port D so as to divide 70 incoming air current between the sides and the front of the cylinder.

The assembly as shown in Figures 11 and 12 is 75 substantially the same as that represented in Fig-

ures 9 and 10 except that a series of parallel slots g^0 provided with oblique deflectors r are positioned across the whole front of the cylinder and a sliding sheet-metal screen s is mounted to move across any number of slots g^0 desired (the mechanism for displacing screen s is not shown but will be readily suggested by the screen operating devices shown in Figures 1 to 7).

In the modification illustrated in Figure 13, front screen g is split into two sections g^1 and g^2 separated by an opening F. A screen q^1 serves to divert the incoming air to both sides of the cylinder.

Figures 14 and 15 show a cooling system of the type represented in Figure 11 applied to the front of a star-shaped aviation motor assembly, the rear portion of the cylinders being cooled by an assembly of the type represented in Figures 5 and 6. The front shield c is in this case provided with a plurality of parallel slots g^0 provided with deflectors r as in the arrangement shown in Figs. 11 and 12. Positioned in front of the shield c is a shield s having fan shaped portions. The shield s is movable about a central axis one way or the other by means of Bowden cables e^1 so as to cover or close any number of the slots g^0 as the operator may deem expedient.

The invention is not to be taken as limited to the particular structures shown in any figure of the drawings: thus, heating chamber e may be placed either in front or behind the motor as shown in Figures 1 and 2 or 5 and 6; rear deflectors h in Figures 3 and 4 may replace assembly h , i in Figures 5 and 6 or 14 and 15 and vice versa; any one of the assemblies shown in Figures 8, 9 35 and 10, 11 and 12 or 13 may be used interchangeably in whole or in part; the front portion of the cooling system represented in Figure 14 may be replaced by any one of those represented in Figures 8, 9 or 13 and the rear system by one of the 40 type shown in Figure 3.

The phrase "level of the base of the cylinders" as used in some of the claims is intended to mean the level where the cylinder joins with the crank case.

Whatever be the manner chosen to practically put the invention into realization, it is clearly understood that said invention permits of obtaining, in every case, for the cylinder walls, a substantially constant temperature in all points, 50 and of avoiding that said temperature may be lowered under a value for which condensation of the fuel in the oil would occur.

What I claim is:—

1. In combination with the cylinder of a motor, 55 a screen positioned to intercept air flowing toward said cylinder and acting to deflect said air into the spaces situated on both sides of said cylinder, a deflector positioned to receive the air deflected laterally by said screen and to direct said air toward the back of the cylinder, said deflector and said screen having a free space formed therebetween permitting the entry of air, and an auxiliary deflector positioned to deflect the air entering through said free space toward the front 60 and one side of said cylinder.

2. In combination with the cylinder of a motor, 65 a screen positioned to intercept air flowing toward said cylinder and operative to deflect said air into the spaces situated on both sides of said cylinder, said screen having a slot formed therein and being provided with a deflector portion positioned in line with said slot and obliquely with respect to the screen surface.

3. In combination with a motor assembly pro- 75

- vided with a pair of spaced cylinders and means for directing air against the front of said cylinders, a fixed wall positioned in front of said cylinders and having a first slot formed therein 5 positioned to lie in line with the space between said cylinders, said fixed wall having a second slot formed therein positioned laterally with respect to said first slot and in line with a portion of one of said cylinders.
- 10 4. In combination with a motor assembly provided with a pair of spaced cylinders and means for directing cooling air against the front of said cylinders, a bent, fixed screen system positioned in front of said cylinder and having a plurality 15 of slots formed therein, means operative to cover said slots, and a deflector system positioned to enclose portions of the sides and the backs of each of said cylinders, said deflector system having openings formed therein permitting the discharge of cooling air therethrough at a point situated behind said cylinders.
- 15 5. In connection with an air cooled engine including at least one cylinder, the combination of a screen positioned in front of said cylinder to prevent cold air from impinging on at least the lower portion of the surface of the front part of the cylinder normally to said surface, said screen including means to deflect air flowing toward said cylinder into the spaces on either side of said 20 cylinder, and deflecting walls extending on either side of and at the rear of said cylinder for directing said air substantially tangentially onto the rear part of said cylinder.
- 20 6. In connection with an air cooled engine including at least one cylinder, the combination of a screen positioned in front of said cylinder to prevent cold air from impinging on at least the lower portion of the surface of the front part of the cylinder normally to said surface, said screen including means to deflect air flowing toward said cylinder into the spaces on either side of said cylinder, and deflecting walls extending on either side of and at the rear of said cylinder, said walls being spaced apart so as to leave an outlet gap 25 between them directly behind said cylinder, said walls directing said air substantially tangentially onto the rear part of said cylinder and allowing it to escape through said gap.
- 25 7. In connection with an air cooled engine including at least one cylinder, the combination of a screen provided with at least one slot positioned in front of said cylinder to prevent cold air from impinging on at least the lower portion of the surface of the front part of the cylinder normally to said surface, said screen including means to deflect air flowing toward said cylinder into the spaces on either side of said cylinder, and deflecting walls extending on either side of and at the rear of said cylinder, said walls being spaced apart so as to leave between them an outlet gap behind said cylinder, said walls directing said air substantially tangentially onto the rear part of said cylinder and allowing it to escape through said gap.
- 30 8. In connection with an air cooled engine including at least one cylinder, the combination of a screen positioned in front of at least the lower portion of said cylinder, said screen being provided with at least one slot, deflecting means located behind said slot for preventing the air that passes therethrough from impinging against the front surface of said cylinder normally thereto, said screen including means to deflect the air flowing toward said cylinder into the spaces on either side thereof, and deflecting walls extending 35 on either side of and at the rear of said cylinder, said walls being spaced apart so as to leave an outlet gap between them directly behind said cylinder, said walls directing said air substantially tangentially onto the rear part of said cylinder and allowing it to escape through said gap.
- 35 9. In connection with an air cooled engine including at least one cylinder, the combination of a screen positioned in front of at least the lower portion of said cylinder, said screen being provided with a plurality of slots, deflecting means located behind said slots for preventing the air that passes therethrough from impinging against the front surface of said cylinder normally thereto, 40 said screen including means to deflect the air flowing toward said cylinder into the spaces on either side of said cylinder, and deflecting walls extending on either side of and at the rear of said cylinder, said walls being spaced apart so as to leave an outlet gap between them directly behind said cylinder, said walls directing said air substantially tangentially onto the rear part of said cylinder and allowing it to escape through said gap.
- 40 10. In connection with an air cooled engine including at least one cylinder, the combination of a screen positioned in front of at least the lower portion of said cylinder, said screen being provided with a plurality of slots, deflecting means located behind said slots for preventing the air that passes therethrough from impinging against the front surface of said cylinder normally thereto, 45 said screen including means to deflect the air flowing toward said cylinder into the spaces on either side of said cylinder, and deflecting walls extending on either side of and at the rear of said cylinder, said walls being spaced apart so as to leave an outlet gap between them directly behind said cylinder, said walls directing said air substantially tangentially onto the rear part of said cylinder, and allowing it to escape through said gap, and a deflecting element located on one side of said screen and between it and said cylinder to cause a portion of the air flowing past said side 50 of said screen to flow between the front surface of said cylinder and said screen to the opposite side of said cylinder.
- 50 11. In connection with an air cooled engine including a plurality of radial cylinders, the combination of a stationary screen positioned in front of at least the lower portions of said cylinders, said screen being provided with a plurality of apertures located in front of the spaces between said cylinders, deflecting means behind said apertures for directing the flow of air that passes therethrough substantially tangentially onto the rear parts of said cylinders, and rotary means, coaxially mounted with respect to said cylinders, for closing said apertures.
- 55 12. In connection with an air cooled engine including a plurality of radial cylinders, the combination of a stationary screen positioned in front of at least the lower portions of said cylinders, said screen being provided with a plurality of apertures located in front of the spaces between said cylinders, deflecting means behind said apertures for directing the streams of air that pass therethrough substantially tangentially onto the rear parts of said cylinders, a rotary shutter provided 60 with apertures corresponding with those of said screen coaxially mounted adjacent to said screen and means for moving said shutter with respect to said screen, whereby the first mentioned apertures can be opened or closed.

13. In connection with an air cooled engine including a plurality of radial cylinders, the combination of a stationary screen positioned in front of at least the lower portions of said cylinders, said screen being provided with a plurality of apertures located in front of the spaces between said cylinders respectively, a deflecting wall extending between said cylinders and to the rear thereof for directing the streams of air that pass through said apertures substantially tangentially onto the rear parts of said cylinders, said deflecting wall being provided with outlet openings located directly behind said cylinders for the escape of said streams of air, a rotary shutter provided with apertures corresponding with those of said screen coaxially mounted in adjacent relation to said screen, and means for moving said shutter with respect to said screen, whereby the first mentioned apertures can be opened or closed.
14. In connection with an air cooled engine including a plurality of radial cylinders, the combination of a stationary screen positioned in front of at least the lower portions of said cylinders, said screen being provided with at least one radial slot in front of a portion of each cylinder and with a plurality of apertures located in front of the spaces between said cylinders respectively, a deflecting wall extending between said cylinders and to the rear thereof for directing the streams of air that pass through said apertures substantially tangentially onto the rear parts of said cylinders, said deflecting wall being provided with outlet openings located behind said cylinders for the escape of said streams of air, a rotary shutter provided with apertures corresponding with those of said screen mounted coaxially with said screen in adjacent relation thereto, and means for moving said shutter with respect to said screen, whereby the first mentioned apertures can be opened or closed.
15. In connection with an air cooled engine including a plurality of radial cylinders, the combination of a stationary screen positioned in front of at least the lower portions of said cylinders, said screen being provided with a plurality of radial slots in front of each cylinder and with a plurality of apertures located in front of the spaces between said cylinders respectively, a plurality of deflectors carried by said screen behind said slots for directing the air flowing toward said cylinders obliquely onto the cylinders, a deflecting wall extending between said cylinders and to the rear thereof for directing the streams of air that pass through said apertures substantially tangentially onto the rear parts of said cylinders, said deflecting wall being provided with outlet openings located directly behind said cylinders for the escape of said streams of air, a rotary shutter provided with apertures corresponding with those of said screen mounted coaxially with said screen in adjacent relation thereto, and means for moving said shutter with respect to said screen, whereby the first mentioned apertures can be opened and closed.
16. In combination with the cylinder of a motor, a screen positioned to intercept air flowing toward said cylinder and acting to deflect said air into the spaces situated on both sides of said cylinder, said screen having a slot formed therein, and means operative to cover said slot.
17. In combination with an air cooled engine including a plurality of spaced radial cylinders, a stationary screen positioned in front of at least the lower portions of said cylinders, said screen being provided with a plurality of apertures located in front of the spaces between said cylinders and extending substantially to the level of the base of the cylinders and adapted to admit the cooling air in a substantially tangential direction against the walls of the cylinders.
18. In combination with an air cooled engine including a plurality of radial cylinders, a stationary screen positioned in front of at least the lower portions of said cylinders, said screen being provided with a plurality of apertures located in front of the spaces between said cylinders and adapted to admit the cooling air in a substantially tangential direction against the walls of the cylinders, and means for regulating the air flow passing through said apertures.
19. In combination with an air cooled engine including a plurality of radial cylinders, a stationary screen positioned in front of at least the lower portions of said cylinders, said screen being provided with a plurality of apertures located in front of the spaces between said cylinders and adapted to admit the cooling air in a substantially tangential direction against the walls of the cylinders, and rotary means, coaxially mounted with respect to said cylinders, for regulating the air flow passing through said apertures.
20. In combination with an air cooled engine including at least one cylinder, a screen positioned in front of said cylinder to prevent cold air from impinging on at least the lower portion of the surface of the front part of the cylinder, said screen being provided laterally of the cylinder with means to admit the cooling air along the whole axis of the cylinder and in a direction transversely of the axis and substantially tangential to the walls of the cylinder.
21. In combination with an air cooled engine including at least one cylinder, a screen positioned in front of said cylinder to prevent cold air from impinging on at least the lower portion of the surface of the front part of the cylinder, said screen being provided laterally of the cylinder with means to admit the cooling air along the whole axis of the cylinder and in a direction transversely of the axis and substantially tangential to the walls of the cylinder, and means for regulating the air flow admitted against the cylinder.
22. In combination with an air cooled engine including a plurality of radial cylinders, the combination of a stationary screen positioned in front of at least the lower portions of said cylinders, said screen being provided with a plurality of apertures located in front of the spaces between the cylinders and extending substantially to the level of the base of the cylinders, and deflecting means behind said apertures for directing the flow of air that passes therethrough substantially tangentially onto the rear parts of the cylinders.
